UNITED STATES PATENT OFFICE.

FRANK HIXSON, OF ASHLAND, OHIO, ASSIGNOR OF ONE-HALF TO H. L. MCCRAY, OF ASHLAND, OHIO.

ADJUSTABLE CHAFFER OR SIEVE.

SPECIFICATION forming part of Letters Patent No. 694,148, dated February 25, 1902.

Application filed January 21, 1901. Serial No. 44,042. (No model.)

To all whom it may concern:

Be it known that I, FRANK HIXSON, a citizen of the United States, residing at Ashland, in the county of Ashland and State of Ohio, have invented certain new and useful Improvements in Adjustable Chaffers or Sieves, of which the following is a specification.

My invention relates to chaffers or sieves for threshing-machines such as are used in separating grain and the like from straw and chaff, the object being the production of improved means for performing the requisite functions, said means to be cheap in first cost, simple in construction, strong and durable, 15 adapted to be adjustably secured within a shoe, whereby the entire body of the same or either end thereof can be raised or lowered relative to the said shoe, and which shall be provided with operating mechanism for the 20 slats located partly beneath the frame or body of the chaffer or sieve and when applied to a sieve so disposed that part of the said mechanism will lie on the outside of the shoe.

With this end in view my invention consists in certain novelties of construction and 25 combinations of parts hereinafter set forth and claimed.

The accompanying drawings illustrate one example of the physical embodiment of my 30 invention constructed according to the best modes I have so far devised for the practical application of the principles.

Figure 1 is a top plan view of my improved chaffer or sieve, a fragment of a shoe, and 35 the operating mechanism, the frame of the sieve being broken away on one side of the divisional piece. Fig. 2 is a longitudinal sectional view of Fig. 1, shown in elevation, the side of the shoe also being shown broken 40 away. Fig. 3 is a cross-section of Fig. 1, taken on the line of one of the shafts. Fig. 4 is a perspective view of a slat detached from the frame and shown in an inverted position, so as to disclose the shaft and crank more 45 clearly.

Referring to the several figures of the drawings, the numeral 1 designates the shoe.

2 designates the side pieces of the frame, made with upper beveled surfaces, so that 50 grain or the like falling upon them will be

guided downwardly upon the slats; 3, the end pieces of the frame.

4 is a divisional piece extending between the end pieces and having a double-beveled edge to guide the grain downwardly. 55

5 designates bearings or holes for the shafts in the side pieces; 6, bearings for shafts in the divisional piece; 7, guards or deflectors on one end piece of the frame; 8, the upwardly-turned edges of the guards. 60

9 is a slat made, preferably, of sheet metal or the like; 10, a seat in a slat for the reception of a shaft, the same being formed by striking up the metal on a line longitudinally of the slat; 11, a shaft, in this instance made 65 in two pieces or parts, the end of one being bent and extended to lie along the side of the body of the other; 12, a crank, in this case integral with one of the parts of the shaft, but which can be made separately and attached, 70 if so desired; 13, clips for retaining the shaft in its seat, the same being made by cutting slits in the metal and bending the portion between the slits downwardly, as shown, or by forming separate pieces and securing them 75 in position.

14 indicates solder, which is applied at the meeting surfaces of the shaft and slat and clips for the purpose of holding the shaft rigidly to the said seat, so one cannot move relative to the other. 80

15 indicates fingers formed along one edge of the slat.

16 indicates prongs formed by slitting or cutting the edge of the metal and bending 85 the parts between the slits downwardly at approximately right angles to the plane of the slat, and the said prongs, as well as the fingers 15, should preferably be of a tapering shape. 90

17 indicates guide-notches made in the rear edge of a slat and which receive and guide the prongs of the slat located in the rear, these notches preferably having inclined sides, as shown, so that the parts will not bind when 95 the slats are rotated.

18 is a rocker-bar located beneath the frame; 19, a pin and cotter; 20, a lower connecting-bar; 21, an arm to which bar 20 is pivoted; 22, a journal fitting a bearing in the side piece 100

of the frame and to which arm 21 is rigidly secured; 23, an upright rigidly secured to the journal 22 in any desirable way; 24, an upper connecting-bar pivoted to the upright; 25, a 5 crank-arm to which the upper connecting-bar 24 is also pivoted; 26, a shaft journaled in the shoe; 27, a lever-arm secured to the shaft and made of a flat bar of metal, and 28 is a toothed rack located upon the outside of the 10 shoe.

- To adjust the series of slats, the lever-arm 27 is sprung outwardly and disengaged from the toothed rack 28 and then moved upwardly or downwardly. The motion of the lever 15 rocks the shaft 26 and its arm 25, imparts a longitudinal motion to the upper connecting-bar 24, rocks the upright 23, journal 22, and arm 21, and by the latter imparts a longitudinal motion to the lower connecting-bar 20. 20 The bar 20, being pivoted to the rocker-bar 18, imparts a longitudinal motion to the said rocker-bar, and as the ends of the cranks 12 are pivoted in the bar 18 the shafts 11 are caused to rotate in their bearings and simultaneously 25 change the positions of the slats 9 one relative to another. It is obvious that by the movement of the lever-arm 27 the open spaces between the slats can be increased or diminished. 30 From the foregoing description it will become obvious that I have produced a chaffer or sieve which fulfils all the conditions hereinbefore set forth as the purpose of my invention and which possesses other desirable 35 and valuable features and characteristics of construction.

The operating mechanism is partly located outside the shoe, where it can be manipulated when the machine is in operation. The 40 rocker-bar is placed under the frame out of the way, where it will not interfere with the material which passes over the slats of the sieve on its upper surface, and the connecting parts of the slat-operating mechanism 45 permit the body, as well as the ends, of the sieve to be raised or lowered in the shoe. When the frame is used in connection with a chaffer, I may omit the upper connecting-bar and the crank and substitute means for 50 adjusting and holding the bar and the slats in proper fixed position.

It is of course understood that the sieve-frame may be divided into any desirable number of sections and that it may be supported in the shoe by any suitable means. 55

While I have illustrated and specifically described only one example of the physical embodiment of my invention, I do not thereby intend to restrict the scope thereof to such 60 example or the exact details of construction illustrated, inasmuch as changes and modifications, additions, and substitutions may be made, or even parts omitted, at the will of the manufacturer, without constituting a substantial departure.

What I claim is—

1. The combination in a chaffer or sieve, of

a frame; a series of metallic slats rigidly secured to shafts and the shafts journaled in the frame; and means for rotating the slats 70 and shafts simultaneously; the said slats having one edge provided with fingers 15, and prongs 16 which lie in a plane substantially at right angles to the plane of the surface of the slat, and the said slats so arranged in the 75 frame that the fingers 15 of each slat will overlap the edge of an adjacent slat.

2. The combination in a chaffer or sieve, of a frame; a series of metallic slats rigidly secured to shafts and the shafts journaled in 80 the frame; and means for rotating the shafts and slats simultaneously; the said slats having one edge provided with downwardly-projecting prongs 16, which lie in a plane at an angle to the plane of the slat, and the other 85 edge provided with notches 17 formed in the body thereof; the said slats being so arranged in the frame that the prongs of one slat normally occupy positions within the notches of an adjacent slat. 90

3. The combination in a chaffer or sieve, of a frame; a series of metallic slats rigidly secured to the shafts and the said shafts journaled in the frame; and means for rotating the shafts and slats simultaneously; the said 95 slats having one edge provided with fingers 15 and prongs 16, and the other edge with notches 17, and the slats so arranged in the frame that the prongs of one slat will occupy positions within the notches of an adjacent 100 slat and the fingers 15 overlap the edge of an adjacent slat.

4. The combination with a shoe, of a chaffer or sieve having a frame; a series of metallic slats rigidly secured to shafts and the shafts 105 journaled in the frame; each of said slats having a plane surface and the metal thereof struck up in a longitudinal line intermediate its parallel edges to form a seat 10 for a shaft, and a shaft rigidly secured in said seat by 110 solder and clips; and each of said slats having a crank 12; a rocker-bar 18 located beneath the frame and slats to which the cranks 12 of the slats are pivoted; a lever located on the outside of the shoe; and means uniting 115 the lever and the rocker-bar 18 whereby the slats may be adjusted simultaneously.

5. The combination with a shoe, of a chaffer or sieve; and means for operating the slats of the chaffer or sieve; the said chaffer or sieve 120 having a frame, slats rigidly secured to shafts journaled in the frame and each shaft provided with a crank 12 which is pivoted to a rocker-bar 18; and the means for operating the slats of the sieve or chaffer consisting of 125 a lever and crank-arm, a journal located in a side piece of the frame and having arms, an upper connecting-bar, and a lower connecting-bar.

6. The combination in a chaffer or sieve, of 130 a frame; a series of metallic slats rigidly secured to shafts and the said shafts journaled in the frame; and means for rotating the shafts and slats simultaneously consisting of

cranks 12 on the under surfaces of the slats, a rocker-bar 18 beneath the frame to which the cranks are pivoted, an upright 23, a journal 22 located in the side of the frame, an arm 21 on the journal 22; a connecting-bar 20 pivoted to the rocker-bar 18 and the arm 21, and means whereby the upright 23 can be held in a fixed position when shifted toward the right or left relative to the frame.

10 7. The combination in a chaffer or sieve, of a frame; a series of sheet-metal slats rigidly secured to shafts so that the slats will move with the shafts without lost motion, and the said shafts journaled in the frame; and means 15 for rotating the shafts and slats simultaneously; the said slats being arranged parallel

in the frame and one edge of each slat having downwardly-projecting prongs or fingers which are located close to the edge of an adjacent slat and normally extend below said adjacent slat, the arrangement being such that, when the slats are rotated and caused to occupy positions oblique to the frame, openings will be made between the prongs and the edge of a slat adjacent the said prongs 25 through which currents of air can pass.

In testimony whereof I affix my signature in presence of two witnesses.

FRANK HIXSON.
